LOCOMOTIVE SPARK ARRESTER

Leon H. Jones, Norfolk, Va.

Application June 29, 1944, Serial No. 542,783

3 Claims. (Cl. 110—123)

The present invention relates generally to new and useful improvements in railroad locomotives of the steam type, and has for its primary object to provide, in a manner as hereinafter set forth, novel means for preventing the discharge of sparks, cinders, etc., from the smoke stack.

Another very important object of the invention is to provide a locomotive of the aforementioned character comprising unique means, controlled from the cab, for shutting off the major portion of the draft to the stack when desired as, for example, when starting a heavy train.

Other objects of the invention are to provide a spark arresting and draft controlling means for locomotives of the aforementioned character which will be comparatively simple in construction, strong, durable, highly efficient and reliable in operation, compact and which may be manufactured at low cost.

All of the foregoing and still further objects and advantages of the invention will become apparent from a study of the following specification, taken in connection with the accompanying drawing, wherein like characters of reference designate corresponding parts throughout the several views, and wherein:

Figure 1 is a view in transverse section through the front end portion of a locomotive equipped with the present invention.

Figure 2 is a fragmentary view in longitudinal section.

Figure 3 is a detail view in side elevation of the air or steam unit which closes the intake port cover.

Referring now to the drawing in detail, it will be seen that reference character 1 designates the front portion of the usual casing of a locomotive boiler. Mounted in the front portion of the casing 1 is the usual smoke box 2 provided with the screen 3 on its front, etc.

Rising from the casing 1 is a stack 4. In the embodiment illustrated, the stack 4, including the petticoat, etc., is in one piece. Projecting upwardly in the lower portion of the stack 4 is the usual exhaust nozzle 5.

Projecting forwardly from the stack 4 in the smoke box 2 is an intake port or neck 6. The forward end portion of the intake neck 6 has mounted therein a spark and cinder arresting screen 7 of suitable mesh. Also mounted on the forward end of the intake neck 6 is a plurality of forwardly projecting blocks 8, the purpose of which will be presently set forth.

Brackets 9 are mounted on the front portion of the stack structure 4 below the intake neck 6. A

transverse shaft 10 is journaled in the brackets 9. Fixed on the shaft 10 between the brackets 9 is a cover 11 for the intake neck 6. The cover 11 is prevented from completely closing the intake neck 6 by the spacing blocks 8 with which said cover is engageable.

The shaft 10 projects through one side of the casing 1 and has fixed thereon a pinion gear 12. Mounted on this side of the casing 1 is a power unit 13 for closing the cover 11. The unit 13 includes a longitudinal air or steam cylinder 14 in which a piston 15 is operable. The piston 15 is fixed on one end of a rack bar 16 which is maintained in engagement with the pinion gear 12 by a guide roller 17. A pipeline 18 connects the cylinder 14 on one side only of the piston 15 to the source of air or steam. A control valve (not shown) in the cab of the locomotive is interposed in the line 18.

It is thought that the operation of the invention will be readily apparent from a consideration of the foregoing. Briefly, when the locomotive is under way and running easily, the cover 11 is suspended in open position, as shown in full lines in Figure 2 of the drawing. Smoke from the box 2 enters the stack 4 through the intake neck 6. Sparks, cinders, etc., in the smoke are arrested by the screen 7 and drop by gravity to the lower portion of the smoke box 2. Should it be desired to shut off the major portion of the draft to the stack 4, as when starting a heavy train and the sparks and cinders as well as the smoke are excessive, the engineer opens the valve in the line 18 to admit air or steam to the forward end portion of the cylinder 14. Thus, the piston 15 is moved rearwardly, as suggested by the arrows in Figure 3 of the drawing, for rotating the shaft 10, through the rack bar 16 and the pinion gear 12, in a direction to swing the cover 11 upwardly to operative position against the spacing elements 8, as suggested in dotted lines in Figure 2 of the drawing. It will thus be seen that the intake neck 6 is nearly but not entirely closed. When the air or steam is exhausted from the cylinder 14 the cover 11 swings downwardly to open position by gravity.

It is believed that the many advantages of a locomotive spark eliminating and smoke stack draft controlling means constructed in accordance with the present invention will be readily understood and although a preferred embodiment is as illustrated and described, it is to be understood that changes in the details of construction and in the combination and arrangement of parts

may be resorted to which will fall within the scope of the invention as claimed.

What is claimed is:

1. In a spark arrester, in combination with the discharge stack of a locomotive having a screened lateral intake opening, a transverse shaft journaled adjacent the stack below the horizontal plane of the intake opening, a cover for the intake opening fixed on said shaft, a pinion gear fixed on the projecting end portion of the shaft, a cylinder, for the reception of a fluid under pressure, mounted in cooperative relation to the cylinder, a piston operable in the cylinder, a rack bar connected to the piston and engaged with a gear on said shaft for rotating the shaft in a direction to close the cover, said cover being operable by gravity to open position, and projections mounted around the intake opening for engagement by the cover for preventing said cover from completely closing said intake opening.

2. In a spark arrester, in combination with the discharge stack of a locomotive having a screened lateral intake opening, means for controlling the communication between the intake opening and the stack, said means including spaced projections surrounding the said intake opening and a cover movable bodily toward and from said opening, whereby to prevent complete closing of the opening when the cover is in contact with said projections and to vary the greater capacity of the opening when the cover is moved from said such contact.

3. The structural combination as set forth in claim 2 and further including with the control means for the intake opening of the stack, means for selectively operating said cover to and from covering position.
